UNITED STATES PATENT OFFICE

126,095

DESIGN FOR AN ILLUMINATED KEY HOLDER OR SIMILAR ARTICLE

John Stewart Marshall, Ipava, Ill.

Application June 27, 1940, Serial No. 93,292

Term of patent 3½ years

To all whom it may concern:

Be it known that I, John Stewart Marshall, a citizen of the United States, residing at Ipava, in the county of Fulton and State of Illinois, have invented a new, original, and ornamental Design for an Illuminated Key Holder or Similar Article, of which the following is a specification, reference being had to the accompanying drawing, forming part thereof.

Figure 1 is a top plan view of an illuminated key holder or similar article and showing my new design.

Figure 2 is a side elevational view thereof.

Figure 3 is a bottom plan view thereof.

Figure 4 is a view similar to Fig. 3 but showing one of the key-carrying slides in projected position, said key-carrying slides being in retracted position in the other figures.

Figure 5 is a front end elevational view.

I claim:

The ornamental design for an illuminated key holder or similar article, as shown and described.

JOHN STEWART MARSHALL.
